UNITED STATES PATENT OFFICE.

ERASTUS HIBBARD, OF SOUTH BARRE, NEW YORK.

MACHINE FOR FINISHING STAVES.

SPECIFICATION forming part of Letters Patent No. 281,066, dated July 10, 1883.

Application filed December 30, 1880. (No model.)

To all whom it may concern:

Be it known that I, ERASTUS HIBBARD, of South Barre, in the county of Orleans and State of New York, have invented a new and useful Improvement in Machines for Finishing Staves, of which the following is a specification.

My improved machine is designed for the work of chamfering, leveling, and crozing 10 staves for barrels and tubs.

The object of the improvement is to construct a machine that shall finish the stave complete, so that when the barrel or tub is set up and trussed it is ready to receive the head 15 without the use of the usual hand-tools for leveling, chamfering, and crozing. Further, the object is to do the work more perfectly than can be done by hand, especially to give uniform depth of croze in barrels having staves 20 of varying thickness, instead of making the croze too deep in thin staves and too shallow in thick ones, as is generally the case in hand operations. My improved machine combines a revolving mandrel carrying the tools and 25 a feed-bed with traveling belts for carrying the staves. The parts are made adjustable and self-adjusting according to the thickness of stave, as hereinafter described and claimed.

In the accompanying drawings, Figure 1 is 30 aside elevation of my improved machine. Fig. 2 is a plan view of the same. Fig. 3 is a vertical transverse section on line $\alpha\alpha$ of Fig. 1. Fig. 4 is a cross-section of the mandrel, showing 35 the cutting-tools; and Fig. 5 is a detail showing the beveled fingers of the presser-bar.

Similar letters of reference indicate corresponding parts.

A is a suitable frame supporting the main bed a , upon which are longitudinal tracks b , 40 preferably four in number, and extending the whole length of the bed.

At the ends of the bed, and supported in suitable boxes, are shafts $c c$, having fixed pulleys $c' c''$, that carry endless bands or chains d . 45 The shafts c are placed so that the bands d extend in line with the tracks b , and with their upper portion resting, or nearly so, on the tracks. The bands may be of flexible material or jointed links, and those at the ends of 50 the shafts are formed with links of a form to take hold upon the pulleys c'' , which latter are

made of angular form, so that the bands cannot slip, and will transmit the power applied to one shaft c to the other. The bands or chains are provided at suitable intervals with 55 projecting lugs d' , by which the staves are carried forward. The boxes carrying shafts c are fitted for movement lengthwise of frame A by means of adjusting-screws v , so that the belts d can be tightened when necessary. 60

At about the mid-length of the machine the mandrel B is fitted across frame A in boxes.

Upon each end of the mandrel is a head, e , and a circular saw, f , outside of and abutting against the head. The heads e have four or 65 more faces, to which the beveled cutters u , that chamfer the staves, are adjustably secured. On the side of the head are fixed the crozing-cutters t , the ends of which project radially of the head and beyond the cutters u . For tub- 70 staves they will be placed at both ends and one or two circular saws placed at the mid-length of the mandrel, as shown at g , for the purpose of cutting the stave in two.

Above the tracks b a presser-bar, h , is supported transversely of the machine by arms or brackets i , that rise from the side of frame A . The brackets are provided with screws i' , that enter the ends of bar h , whereby the bar is supported and may be adjusted to and from 80 the tracks b .

To the under side of bar h , over the two middle tracks b , fingers k are fixed, which are beveled at each end in the direction of feed, so that the staves shall readily pass beneath the 85 fingers and be pressed closely upon the track.

At the ends of bar h , above heads e , adjustable plates l are fitted for holding the ends of the staves down against the action of the tools. The two side tracks b , as shown most clearly 90 in Fig. 3, are raised slightly at their mid-length, and are sustained by springs b' , secured in bed a . The object of this feature is to allow self-adjustment of the tracks to the thickness of staves, so that stave thicker than allowed for 95 by the adjustment of plates l can pass, the distance between the under side of the plates and the cutting-tools remaining the same, the croze being cut deeper to correspond with the increased thickness. 100

The mandrel carrying the tools and the shafts $c c$, carrying belts, are driven from a shaft, m ,

that is sustained in boxes at the lower portion of the receiving end of the machine, to the pulley m' of which power is to be applied. The mandrel is driven by a straight belt directly 5 from a pulley, n' , on shaft m , while from a second pulley, n , on shaft m a straight belt passes to a secondary shaft, o , fitted at the delivery end of the machine, carrying a pinion that meshes with a gear-wheel, o' , on the shaft c 10 above it, so that the bands or chains d are moved in the proper direction.

For the purpose of bringing the staves to the machine from a distance and delivering them after finishing, I use endless belts p , 15 passing around pulleys p' on shafts c , and sustained at the point where the staves are received or delivered by pulleys on a drum or shaft, q , that is sustained in a portable or fixed frame, r . The belts p are thereby moved in 20 the same direction as the feed-belts d , so that the staves will be brought to the feeding end of the machine for being placed by hand upon belts d , and, after being sawed, chamfered, and crozed, will be carried to the delivery-belts p , 25 which deliver them at the place desired.

In operation the barrel-staves, being placed on belts d , are carried forward beneath bar h , and while held down by the fingers and plates l the ends are squared by the saws f to give them 30 uniform length, and both ends chamfered and crozed by the cutters. The saws f may be upon hubs adjustably connected on the shaft, so that the length of finished stave can be varied.

35 In making tub-staves the crozing and chamfering cutters will be fitted at both ends of mandrel B , so that both ends of the stave shall be operated upon, and the saw or saws g will be secured on the middle portion of the shaft, 40 so that the stave will be cut in two at the same time, thereby finishing two tub-staves at once.

To guide the staves and insure their proper presentation to the saws, there is attached to one side of frame A , at the feeding end of the 45 machine, a fixed guide-piece, r , extending lengthwise and above the level of the tracks, and at the other side is attached a spring-arm, s , the outer end of which extends toward the saw and the center of the machine. The staves 50 take by one end against the fixed guide r and by the other end against s , which gives way to accommodate inequalities in length. The staves are thus presented squarely and evenly to the tools.

This machine will accomplish the work rapidly and uniformly, and requires no skilled labor for its operation. The staves, when trussed for completing the barrel or tub, will be uniform in their chamfered portion and in diameter of croze, and the thickness of material outside of croze in each stave will be uniform, instead of some being cut nearly through and others too shallow, as is the case when the croze is cut while the staves are trussed up in wooden truss-hoops, as such hoops seldom remain true circles.

I am aware that an adjustable pressure-bar has heretofore been employed in stave-finishing machines, and I therefore do not claim such invention.

Having thus described my invention, I claim as new and desire to secure by Letters Patent—

1. In a machine for finishing staves, the combination, with the bed a and revolving mandrel B , carrying the finishing-tools, of the longitudinal tracks b , the endless chains d , provided with the projecting lugs d' , and the adjustable presser-bar h , provided with the fingers k , substantially as herein shown and described.

2. In a machine for finishing staves, the combination, with the revolving mandrel B , having saws f and cutters $t u$ at each end, of saws g , mounted on the said shaft at the middle of its length, substantially as herein shown and described, whereby provision is made for finishing two tub-staves at once, as set forth.

3. In machines for finishing staves, the adjustable bar h , provided with fingers k , and adjustable plates l , combined with bed a , tracks b , feed-bands d , and tool-mandrel B , substantially as and for the purposes set forth.

4. In machines for finishing staves, the raised side tracks b , provided with springs b' , combined with feed-bands d , presser-bar h , bed a , and mandrel B , sustained by the bed, substantially as and for the purposes set forth.

5. In a machine for finishing staves, the combination, with the endless chains d , provided with the projecting lugs d' , and the mandrel B , carrying the finishing-tools, of the adjustable presser-bar h , provided with the fingers k , having beveled ends, substantially as and for the purpose set forth.

ERASTUS HIBBARD.
